DUPLEX MOLDING SANDER COMPANY, OF HORNELL, NEW YORK, A CORPORATION
OF NEW YORK.

SANDING AND POLISHING MACHINE.

1,124,657.

Specification of Letters Patent.

Patented Jan. 12, 1915.

Continuation of application Serial No. 716,647, filed August 23, 1912. This application filed March 12, 1914. Serial No. 824,218.

To all whom it may concern:

Be it known that we, JOSEPH C. PRIMS and WILLIAM F. SMITH, citizens of the United States, residing at Hornell, in the county of Steuben and State of New York, have invented a new and useful Sanding and Polishing Machine, of which the following is a specification.

The invention relates to improvements in sanding and polishing machines, and the present application is a continuation of an application filed by us August 23, 1912, Serial No. 716,647, for the same invention.

The object of the present invention is to improve the construction of sanding and polishing machines and to provide a simple, efficient, and comparatively inexpensive machine, adapted to permit the use of coarse and fine abrasive or polishing material at the same time, and capable of easy adjustment whereby sand papering or like abrasion of the surfaces of molding or other material may be effected.

A further object of the invention is to provide a machine of this character in which the operation of sand papering or polishing will be continuous and in which the feeding in and feeding out of the material operated upon may be effected without adjusting or altering the position of the abrasive or polishing means and without stopping the machine.

Another object of the invention is to provide a machine for sanding or polishing moldings and other stock capable of operating at a high speed with minimum vibration, whereby a maximum amount of material may be operated on in a given length of time, and in which, owing to the relatively high speed of the sanding or polishing elements, only a small amount of the abrasive or polishing material will be required on the stock, thereby reducing the consumption of such polishing or abrasive material to a minimum.

A further object of the invention is to provide a sanding and polishing machine in which the movements of the elements carrying the abrasive or polishing material will be confined within a stroke of from one inch and a half to three inches in length, or thereabout, so that the molding or other stock operated upon will have a uniform surface.

A further object of the invention is to provide mechanism adapted to actuate two

pieces of abrasive or polishing material and move the same over the molding or other stock in opposite directions one to the other at all times, so that the feeding in and feeding out of such molding or other stock may be constant and will not be affected by the rubbing action of the abrasive or polishing material on the said molding or other stock.

With these and other objects in view the invention consists in the construction and novel combination of parts hereinafter fully described, illustrated in the accompanying drawings, and pointed out in the claims hereto appended, it being understood that various changes in the form, proportion, size and minor details of construction, within the scope of the claims, may be resorted to without departing from the spirit or sacrificing any of the advantages of the invention.

In the drawings: Figure 1 is a front elevation of a sanding and polishing machine constructed in accordance with this invention. Fig. 2 is a rear elevation of the same. Fig. 3 is a plan view of the machine. Fig. 4 is a central longitudinal sectional view of the same. Fig. 5 is a central transverse sectional view of the machine. Fig. 6 is an enlarged detail vertical sectional view on the line 6-6 of Fig. 1. Fig. 7 is a similar view on the line 7-7 of Fig. 1. Fig. 8 is an enlarged detail sectional view taken longitudinally of one end of the machine, illustrating the arrangement of the upper and lower feed rollers with relation to the grinding and polishing elements. Figs. 9 and 10 are detail sectional views illustrating the manner of adjustably mounting the lower feed roller. Fig. 11 is a detail horizontal sectional view through one of the grinding and polishing elements. Fig. 12 is a detail plan view of the train of gearing for transmitting motion from the pulleys to the upper and lower feed rollers. Fig. 13 is a plan view of the friction clutch for throwing the machine into and out of operation. Fig. 14 is a detail sectional view illustrating the construction of the belt tightener.

Like numerals of reference designate corresponding parts in all the figures of the drawings.

In the accompanying drawings, in which is illustrated the preferred embodiment of the invention, 1 designates a main frame comprising a hollow central supporting col-

umn 2 and a hollow longitudinal elongated top portion 3 having a central suction chamber 4 and hollow terminal portions 5 separated from the suction chamber by transverse webs or partitions 6. The supporting column 2 is also provided at the top with a horizontal web or partition 7 constituting the bottom of the suction chamber. The main frame of the machine is provided at the rear wall of the suction chamber with an opening 8 and it has a coil or flange 9 extending outwardly therefrom and designed to be connected with a suitable vacuum suction device. The front portion of the top 10 of the main frame constitutes a table 11 and the main frame is provided at the back of the table 11 with hooded suction inlet openings 12 of substantially oblong form, opening or facing toward the front and extending longitudinally of the machine and located in rear of front and rear sanding and polishing elements 13 and adapted to convey away the dust. The main frame of the machine is also provided at the front 25 wall of the suction chamber 4 with an enlarged opening 14, normally covered by a removable closure plate 15 secured by screws or other suitable fastening device to the main frame and adapted to be detached 30 to permit ready removal of dust accumulating within the suction chamber 4.

Mounted upon the top of the machine, at the center thereof, is a bearing bracket 16 secured by bolts or other suitable fastening device to the main frame at the rear portion of the top 10 and provided with a front casing 17 having a rearwardly extending approximately L-shaped arm 18 composed of a lower inner horizontal portion and an outer upwardly extending vertical portion terminating in a bearing 19 arranged in alignment with the front casing 17 and receiving the rear end of a double crank shaft 20. The crank shaft 20 is journaled at its front end in a bearing 21 of the casing, and the bracket is provided at the back of the casing with an intermediate bearing 22, which receives the central portion of the double crank shaft 20. The crank shaft 20 is provided with two cranks or crank bends 23, designed to be of a length to reciprocate the sliding shoes or elements from an inch and a half to three inches or thereabout and disposed diametrically opposite each other 55 and connected by rods 24 with the sanding and polishing elements 13, whereby when the crank shaft is rotated, the sanding and polishing elements will be simultaneously reciprocated in opposite directions, so 60 that the grinding and polishing action of each of the said elements 13 will counteract the other, and thereby prevent such sanding and polishing of the material from interfering with the feeding of the latter into 65 and out of the machine. The casing 17 is

provided with a removable top portion or cover 25 and the rear and intermediate gearings 19 and 22 are provided with detachable upper sections or caps. This construction affords ready access to the crank shaft. 70 The casing 17, which is approximately cylindrical, houses the cranks or crank bends of the shaft 20, and it is provided at opposite sides with openings 26 through which the connecting rods extend. The casing 17 75 is located above and overhangs the table 11, to permit the molding or other material operated on to pass beneath it.

The bearing bracket is provided at opposite sides of its intermediate portion with spaced vertical dovetailed guides 27 having inwardly beveled side edges and receiving vertically adjustable supports consisting of yokes 28 disposed transversely of the machine and composed of front and rear sides 85 and connecting top portions, the rear sides being provided at their inner opposite faces with vertical dove-tailed grooves 29 to receive the vertical guides 27, whereby the yokes are slidably interlocked with and adjustable vertically on the guides 27. The yokes are equipped at the rear walls of the dove-tailed grooves 29 with adjustable wear plates or shims 30 controlled by screws 31 mounted in threaded perforations of the rear walls of the dove-tailed grooves 29 and adapted to be adjusted to take up the wear. The front and rear sides of the vertically movable yokes are equipped with horizontally aligned, longitudinally disposed 100 front and rear arms 32 consisting preferably of rods secured at their inner ends in openings of the sides of the yokes 28 by nuts 33 or other suitable fastening means. The arms 32, which are preferably rounded, extend outwardly from the yokes and they slidably support the reciprocating sanding and polishing elements, which consists of shoes, and present, in their construction, spaced sides or members 34 and a clamp 35 secured to the lower portions of the spaced sides or members and adapted to detachably engage sanding or polishing blocks 36. The spaced sides, which have transversely aligned 105 openings 37, are provided at their tops with longitudinally disposed sleeves 38 slidably arranged on the guiding arms 32 of the yokes. The transversely aligned openings 37 receive transverse pins or pivots 39 which pass through cross heads 40 carried by the outer ends of the connecting rods 24. The cross heads 40 extend across the spaces between the sides 34 of the sanding or polishing shoes, and the connecting rods operate in the spaces between the sides of the yokes 28. Each clamp is composed of a relatively fixed section 41 and an adjustable section 42, the sections being provided at their front and rear sides with upwardly extending longitudinally disposed flanges 43 and 44 and 110

115

120

125

130

having depending transversely disposed inclined flanges 45 and 46 which present downwardly and inwardly inclined faces to the sanding or polishing blocks and form beveled jaws for engaging the same. The flanges 43 are bolted to the spaced sides or members 34, and the other flanges 44 are provided with transversely aligned horizontally disposed longitudinal slots 47 receiving a rod or bolt 48 which pierces the sides 34 and slidably connects the relatively adjustable section 42 of the clamp and the said sides or members 34. The section 42 of the clamp is connected with the relatively fixed section 41 by a longitudinally disposed adjusting screw 48 mounted at one end in a lug 49 of the section 41 and provided at the other end with screw threads 50 for engaging a lug 51 of the adjustable section 42.

20 The inner end of the rod is threaded to engage with the lug of the adjustable section, and the outer end 52 of the rod, which is squared to receive a wrench or other tool, is provided adjacent to the squared portion 25 with a collar which bears against the outer face of the lug 49 of the relatively fixed section 41. The diametrically opposite cranks are arranged as close together as possible, and in order to compensate for the 30 offset position of the connecting rods, the cross head pins 39 are located at a point between the guides 20 and the sanding and polishing blocks, and the metal in the sliding shoes is so distributed that the same will 35 balance along the central plane of the connecting rods. This construction and arrangement will enable the sliding shoes to be reciprocated at a relatively high speed, and at the same time will eliminate lateral 40 and vertical vibration, and it has been found by experience that the adjustable crank shaft may be rotated from eight hundred to twelve hundred revolutions per minute, without appreciable vibration. The sanding and polishing blocks are designed to 45 have portions 36^a shaped to conform to the configuration of the molding or other irregular surfaces covered with suitable abrasive or polishing material.

50 The vertically slidable yokes are limited in their downward movement by vertical manually operable adjusting screws 53 extending through upper and lower vertically aligned lugs 54 and 55 at the rear sides of 55 the yokes and having lower threaded portions 56 for engaging the lugs 55. The upper lugs 54 are equipped with clamping screws 57 which are adapted to engage the upper portions of the screws 53 for securing 60 the same in their adjustment. The screws, which are provided at their upper ends with heads or other suitable operating means, project below the planes of the abrading and polishing blocks 36 and rest upon the top of 65 the table and limit the downward movement of the yokes and the slidable sanding and polishing shoes, and enable the said blocks 36 to bear upon the molding 58 or other stock with the desired pressure. The yokes 28 are also provided with rearwardly extending lugs 59 in which are secured the upper ends or rods 60 extending downwardly to the base of the frame and pivotally connected to rocker arms 61 of transverse rock shafts 62. The rock shafts 62, which are 70 journaled in suitable bearings of the supporting column, are equipped at their front ends with treadles 63 adapted to be depressed by the operator for lifting the sanding and polishing shoes either simultaneously or independently to permit the sanding and polishing blocks to be removed and replaced, or for any other purpose. The treadles are connected at points intermediate of their ends to the lower ends of the locking bars 64, having their upper ends arranged in openings 65 of a keeper 66, and provided with shoulders 67 for engaging the keeper 66 to lock the treadles depressed for maintaining the yokes in an elevated position. 75 The shoulders 67 are preferably formed by notching the locking bars 64, which are arranged in a slightly inclined position, so as to operate as gravity latches to engage the keeper automatically when the treadles are 80 depressed. The locking bars are swung out of engagement with the keeper when it is desired to lower the yokes 28 and the weight of the yokes and the mechanism carried thereby is proportioned so as to counter-balance sufficiently the weight of the treadles and the locking bars to produce the proper pressure of the sanding and polishing blocks 85 on the molding or other stock.

90 The table of the machine is equipped with a laterally adjustable guide bar 68 extending the entire length of the table and provided at its ends with depending lugs 69 and provided at one end with a clamping screw 70 piercing the adjacent lug and detachably 95 engaging the adjacent end of the frame of the machine. The guiding bar, which is laterally adjustable, is adapted to be arranged in different positions on the table 100 to form a guide for the molding or other stock operated on by the machine, and it contacts with front guide rollers 71 and 72 arranged at the front of the machine. The guide roller 71, which operates in a vertical plane, is carried by an oscillatory arm 73 105 pivotally mounted on the main frame of the machine and adjustably secured to the same to maintain the guide roller 71 in the desired position. The guide rollers 72 are carried by horizontal rods or stems 74 which are 110 adjustably mounted on vertically adjustable rods or pivots 75. The horizontal rods or stems 74 are adapted to be rotated and also capable of sliding inwardly and outwardly through the vertical rods or pivots, which 115

120

125

130

are adapted to be raised and lowered and also rotated to coöperate with the horizontal rods or stems 74 in properly positioning the guide rollers 72.

5 The molding or other material is fed into and out of the machine by upper and lower feeding rollers 76 and 77. The lower feed rollers 77, which are located nearer the ends of the table and farther from the sanding 10 elements or shoes than the upper feed rollers, are mounted below the table and project upwardly through slots or openings 78 thereof and extend slightly above the plane of the top of the table, so as to support the molding or other material slightly above the table for enabling the material operated on to be slightly flexed by the upper feeding rollers and held flat against the table, where the material is operated on by 15 the sanding and polishing blocks. A pair of upper and lower feeding rollers is arranged at each end of the machine, and the upper feeding roller 76 is mounted on the front end of a transversely disposed shaft 20 79, journaled in a bearing sleeve 80 of an oscillatory arm 81, which is provided at its pivoted end with a forwardly extending pivot 82 and a rearwardly extending spindle or stub shaft 83 which is arranged concentric with the forwardly extending pivot 25 82. The pivot 82 is mounted in a suitable bearing 84, bolted or otherwise secured to the rear portion of the top of the main frame, and the said pivot 82, which extends 30 into the bearing from the rear end of the same, is provided with a projecting screw 85 on which is mounted a friction disk or washer 86 and a nut 87. The oscillatory arm is equipped with a suitable handle 88 35 and is adapted to be swung upwardly and downwardly to arrange the upper feeding roller in proper position with relation to the lower feeding roller, and it is secured in its adjustment by the friction disk or washer, 40 which is clamped against the front of the bearing 84 by the nut 87. The oscillatory arm 81 extends downwardly and inwardly at an inclination from the pivot 82, and in 45 swinging upwardly to lift the roller to accommodate molding or other stock of increased thickness, the engaging portion of the periphery of the upper feeding roller is carried away from the supporting portion of the periphery of the lower feeding roller, 50 as indicated by the dotted lines *a*—*b* in Fig. 8 of the drawings. This increased distance between the engaging portions of the upper and lower feed rollers enables heavy material to be more readily bent or flexed for 55 forcing the portion operated on by the grinding elements in contact with the table, so that the portion of the material operated on will be maintained in a horizontal position on the table.

60 65 The upper and lower feeding rollers, at

each end of the machine, are simultaneously rotated and positively driven by pulleys 88^a mounted on horizontal stub shafts 89 secured to and extending rearwardly from the main frame of the machine near the ends thereof. The feeding roller driving pulleys, which have grooved peripheries to receive a belt 90, are provided with spokes 91 having laterally bent outer terminal portions which inwardly offset the rims of the driving pulleys 88 from the hubs thereof. Each driving pulley 88 is provided at the inner or front side with a pinion 92, meshing with a gear wheel 93 which is mounted on the stub shaft or spindle 83 of the oscillatory arm 81. The gear wheel 93 is provided, at its front side with a pinion 94 meshing with a gear wheel 95 which is mounted on the stub shaft 89, on which the driving pulley rotates. The gear wheel 95 meshes with a pinion 96 mounted on the shaft 97 of the lower feeding roller 77, and the shaft 79 of the upper feeding roller carries a pinion 98 which meshes with the pinion 94. By this arrangement of gearing the upper and lower feeding rollers are simultaneously driven and the movement of the oscillatory arm, which carries the upper feeding roller, does not interfere with the proper meshing of the gearings. The shaft 97 of the lower feeding roller is journaled in an eccentric bushing 99 which is mounted for rotation in a suitable bearing of the main frame of the machine. The eccentric bushing 99, which is provided with a suitable operating handle 100, which is adapted to be rotated to cause the lower feeding roller to project above the table to a greater or less degree, is secured in its adjustment by a clamping screw 101 mounted on the frame of the machine and engaging the bushing 99, as clearly illustrated in Fig. 10 of the drawings. The lower feeding roller is preferably provided with a serrated peripheral wall. The upper feeding roller is preferably smooth at its periphery, but any desired construction of feeding roller may, of course, be employed. 105 The offset rims of the driving pulleys 88^a partially house the trains of gears for communicating motion from the said pulleys to the feed rollers, and the belt 90 extends from the lower sides of the said pulleys to a lower pulley 102 of a stationary countershaft 103, suitably mounted in the supporting column of the main frame and located below and in the transverse vertical plane of the crank shaft. The countershaft 103, which extends rearwardly from the main frame, receives a power driven pulley 104 and a relatively large main driving pulley 105, which is connected by a belt 106 with a pulley 107, mounted on the crank shaft and arranged in the space between the upwardly extending portion of the L-shaped supporting arm 18 and the intermediate 110 115 120 125 130

bearing 22 of the central bearing bracket. The countershaft 103 is equipped at its outer end with an end thrust bearing 108 having anti-friction balls 109 and forming 5 a stop or abutment for preventing outward movement of the power driven pulley 104 on the countershaft. A friction disk 110, of approximately the diameter of the power driven pulley, is interposed between the latter and the driving pulley 105, which is provided with a smooth friction face 111 for engaging the friction disk 110, whereby the driving pulley 105 is clutched to the power driven pulley. The pulley 102, which is 10 relatively small, is suitably connected to and rotates with the driving pulley 105, whereby the pulleys 102 and 105 will be rotated when the said pulley 105 is clutched to the power driven pulley 104. The pulleys 102 and 105 are preferably formed integral with each other and constitute a single unit, but they may be connected with each other in any other desired manner. The driving pulley is moved outwardly on 15 the countershaft by a shifting lever 112, fulcrumed at an intermediate point and connected at one end with a ball bearing thrust collar 113, and at the other end with a cam lever 114 by a transverse rod 115. The shifting lever 112 is located at the back 20 of the machine, and the rod, which is mounted in suitable openings in one of the end portions 5 of the top of the main frame, extends from the back thereof to the front 25 of the same, its rear end being pivoted to the shifting lever, and the cam lever being similarly connected to the front end of the rod 115. The shifting lever 112 is arranged at an inclination and the lever 114, which has 30 a cam head, is adapted to engage the main frame for operating the upper end of the shifting lever forwardly and forcing the lower end thereof and the thrust collar 113 rearwardly to clutch the main driving pulley 105 to the power driven pulley 104. By 35 manipulating the cam lever 114 the machine is thrown into and out of operation, and this construction obviates the necessity of employing fast and loose pulleys and a pulley shifting device. Also, the power driven pulley is adapted to be connected with any 40 suitable source of power located either above, below or at one side of the counter-shaft.

The machine is equipped with a belt 45 tightening device comprising a rock shaft 116 journaled in suitable bearings of the supporting column of the main frame and extending through the same from front to rear, and provided at its rear end with a crank arm 117 carrying an idler pulley 118 which engages one of the lower stretches or runs of the belt 90. The belt 90 extends horizontally from one of the driving pulleys 88^a to the idler pulley 118, and thence 50 downwardly to the pulley 102. The front end of the operating or rock shaft 116 is provided with an operating handle or lever 119 which is adapted to be operated to partially rotate the shaft 116 to tighten the belt. Also, by swinging the idler pulley 118 downwardly and outwardly, the belt 55 may be slackened to stop or check the feeding of the material when desired. The operating handle or lever 119 is fixed to the front end of the shaft 116, and a fiber washer 120 is interposed between the inner attached end of the operating handle and the frame of the machine. The crank arm 117 is slidably connected with the rear end 60 of the shaft 116 by a key 121 mounted on the end of the shaft and operating in a groove or key way in the arm 117. The rear end of the shaft is provided with a threaded bore or opening 122 for the reception of an adjusting screw 123. The rear end of 65 the shaft 116 terminates short of the rear face of the crank arm 117, and the screw 123 is adapted to be tightened to clamp the crank arm 117 against the frame of the machine, a fiber washer 124 being interposed between the inner end of the crank arm and the frame of the machine. A metallic washer 125 is mounted on the screw and is arranged between the head thereof and the outer face of the crank arm 117. By tightening the screw 123 the crank arm may be 70 secured in any of its adjustments.

What is claimed is:

1. A machine of the class described, including a main frame having a relatively fixed table, positively driven feeding means for carrying the molding along the table, spaced sanding or polishing elements arranged substantially in longitudinal alignment and slidably longitudinally with respect to the feed of the material, and means for simultaneously reciprocating the said elements in opposite directions, whereby the abrasive action of each will counteract the other to prevent such abrasive action from accelerating or retarding the feed of the material through the machine.
2. A machine of the class described, including a main frame having a relatively fixed table, means for positively feeding material along the table, spaced sanding or polishing elements arranged substantially in longitudinal alignment and slidably longitudinally with respect to the feed of the material, a centrally arranged crank shaft located between the said elements and having diametrically opposite cranks, and longitudinally disposed rods connecting the sanding or polishing elements with the cranks of the said shaft, whereby the said elements will be simultaneously reciprocated in opposite directions to cause the abrasive action of each element to counteract the other to prevent them from inter-

ferring with and accelerating or retarding the feeding of the material through the machine.

3. A machine of the class described, including a main frame, vertically movable supports, shoes slidably mounted on the said supports, mechanism connected with the shoes for simultaneously reciprocating the same in opposite directions, adjustable means for limiting the downward movement of the supports, and independent manually operable means connected with the supports for raising and lowering the same.
- 10 4. A machine of the class described, including a main frame, spaced vertically movable yokes, sliding shoes carried by the yokes, a double crank shaft located between the yokes, and rods extending through the 20 yokes and connecting the shoes with the crank shaft.
- 15 5. A machine of the class described, including a main frame, spaced vertically movable yokes having parallel horizontal 25 guiding arms, shoes slidably supported by the guide arms, a double crank shaft mounted between the yokes, and connecting rods connected to the shoes and to the crank shaft.
- 20 6. A machine of the class described, including a main frame, a double crank shaft, vertical guides located at opposite sides of the double crank shaft, yokes slidably mounted on the guides and provided with 35 outwardly extending arms, shoes slidable on the said arms, and connecting rods extending through the yokes and connected to the shoes and to the crank shaft.
- 30 7. A machine of the class described, including a main frame having a central bearing bracket provided with a casing and having spaced vertical guides, yokes slidably mounted on the guides at opposite sides of the casing, a double crank shaft mounted 40 between the yokes and having oppositely disposed cranks located within the said casing, slidable shoes carried by the yokes, and connecting rods extending through the yokes and connected at their outer ends to 45 the shoes and at their inner ends to the said crank.
- 45 8. A machine of the class described, including a main frame, spaced vertically adjustable yokes provided with horizontal 55 guide arms arranged in pairs, sliding shoes composed of spaced sides having openings through which the said arms extend, clamps connecting the sides of the shoes, a central crank shaft, and connecting rods extending 60 from the crank shaft to the shoes and pivoted to the same between the sides thereof.
- 65 9. A machine of the class described including a main frame, a support provided with spaced guide arms, a slidable shoe composed of sides slidably mounted on the guide

arms, and a clamp consisting of a relatively fixed section rigidly secured to the sides of the shoe, and an adjustable section slidably connected to the sides of the shoe.

10. A machine of the class described, including a main frame, spaced vertically slidable supports, horizontally sliding shoes mounted on the supports, vertical adjusting screws carried by the supports and arranged to limit the downward movement of the same, and separate manually operable means connected with the supports for raising the same, said operating means having levers arranged adjacent to each other and adapted to be operated either independently or simultaneously.

11. A machine of the class described, including a main frame, vertically slidable supports, sliding shoes carried by the supports, rock shafts mounted on the main frame and provided with treadles, and separate means for connecting the rock shafts with the supports.

12. A machine of the class described, including a main frame, vertically slidable supports, sliding shoes carried by the supports, mechanism located between the supports and connected with the shoes for reciprocating the same, independently operable means for raising the supports, separate inclined locking bars connected with the said means, and a keeper mounted on the main frame and arranged to coact with the locking bars for retaining the supports in an elevated position.

13. A machine of the class described, including a main frame, vertically slidable supports, sliding shoes carried by the supports, mechanism for reciprocating the shoes, separate rock shafts mounted on the main frame and connected with the said supports, and provided with treadles, a keeper mounted on the main frame, and inclined locking bars connected at their lower ends with the treadles and having their upper ends slidable in the keeper, and provided with means for engaging the same.

14. A machine of the class described, including a main frame provided with a table and having a suction chamber, said main frame being also provided at the back of the table with longitudinally disposed hooded suction inlet openings extending upwardly from the plane of the upper face of the table, sliding shoes arranged above the table opposite the said inlet openings, and means for reciprocating the shoes.

15. A machine of the class described, including a main frame provided with a table, and upper and lower feed rollers, the lower feed roller projecting above the table, and the upper feed roller having its vertical axis spaced inwardly beyond the vertical axis of the lower feed wheel and arranged to engage and flex the material to hold the same flat.

against the table, and sanding or polishing mechanism located above the table in position for operating on that portion of the material which is flat against the said table.

5 16. A machine of the class described, including a main frame having a table, a lower feed roller mounted beneath the table and projecting above the same, an oscillatory arm mounted above the table and extending 10 to a point beyond the vertical axis of the lower feed roller, and an upper feed roller carried by the oscillatory arm and arranged to engage the material at a point spaced from the engaging portion of the lower feed 15 roller, whereby the upper feed roller is adapted to flex the material and hold the same flat against the table, and sanding or polishing mechanism located above the table in position for operating on that portion 20 of the material which is held flat against the said table.

17. A machine of the class described, including a main frame having a table, upper and lower feed rollers arranged at the end 25 portions of the table, the lower feed rollers projecting above the table and the upper feed rollers being inwardly offset from the vertical plane of the axes of the lower feed rollers and arranged to flex or bend the material at spaced points to hold the said material flat against the table, sliding shoes arranged above the table in position for engaging that portion of the material which is flat against the table, and mechanism for 30 simultaneously reciprocating the shoes in opposite directions to cause the abrasive action of one shoe to counteract that of the other and prevent the shoes from affecting the feeding of the material into and out of the 35 machine.

40 18. A machine of the class described, including a main frame having a table, a lower feed roller projecting above the table, an oscillatory arm, an upper feed roller carried by the oscillatory arm and arranged to engage the material beyond the vertical plane of the axis of the lower feed roller to flex the material and hold the same flat against the table, operating means connected 45 with the said arm for raising and lowering the upper feed roller, means for locking the oscillatory arm in its adjustment, and sanding or polishing mechanism mounted above the table in position to operate on that portion 50 of the material which is held flat against the said table.

55 19. A machine of the class described, including a main frame having a table, upper and lower feed rollers arranged in pairs at 60 the end portions of the table, driving pulleys located at the ends of the machine, separate trains of gears for transmitting motion from the driving pulleys to the feed rollers and

for permitting relative adjustment of the said upper and lower rollers, an actuating pulley, and a belt connecting the driving pulleys with the actuating pulley.

65 20. A machine of the class described, including a main frame having a table, sliding shoes, a crank shaft mounted above the table 70 and connected with and reciprocating the sliding shoes, feed rollers arranged at the end portions of the table, a countershaft mounted on the frame and located below the crank shaft, a driving pulley mounted on 75 the countershaft, a power driven pulley also arranged on the countershaft, a friction element or member interposed between the power driven pulley and the driving pulley, means for maintaining the power driven pulley and the driving pulley in frictional engagement with the said friction element or member, and means for transmitting motion 80 from the driving pulley to the crank shaft and to the feed rollers.

85 21. A machine of the class described, including a main frame having a table, sliding shoes, a crank shaft mounted above the table and connected with and reciprocating the sliding shoes, feed rollers arranged at 90 the end portions of the table, a countershaft mounted on the frame and located below the crank shaft, a driving pulley mounted on the countershaft, a power driven pulley also arranged on the countershaft, a friction disk 95 mounted on the countershaft and interposed between the said pulleys, shifting mechanism having a thrust collar for maintaining the said pulleys in engagement with the friction disk, and means for transmitting motion 100 from the driving pulley to the crank shaft and to the feed rollers.

105 22. A machine of the class described, including a main frame having a table, sliding shoes, a crank shaft connected with and reciprocating the shoes, a countershaft, pulleys mounted on the crank shaft and the countershaft, a belt connecting the said pulleys, and a belt tightening device comprising a rock shaft mounted in the frame of the 110 machine and provided at one end with an operating handle, a crank arm slidably mounted on the other end of the rock shaft and having an idler engaging the said belt, and means mounted on the rock shaft for 115 sliding the crank arm on the rock shaft to clamp the said crank arm in its adjustment.

In testimony, that we claim the foregoing as our own we have hereto affixed our signatures in the presence of two witnesses.
